Primary Examiner — Sandra Snapp(74) *Attorney, Agent, or Firm* — Cislo & Thomas, LLP(57) **CLAIM**

I claim the ornamental design for an arm chair, as shown and described.

DESCRIPTION

FIG. 1 is a perspective view of my arm chair;

FIG. 2 is a front view thereof;

FIG. 3 is a right side view, the left side (not shown) is a mirror image thereof;

FIG. 4 is a rear view thereof; and,

FIG. 5 is a top view of my arm chair.
